FINDING FOR CLASPS

Filed Oct. 28, 1931

FIG. 1

FIG. 2

FIG. 3

INVENTOR

ABRAHAM SAVITZKY
BY HIS ATTORNEY
Edward Gottlieb

UNITED STATES PATENT OFFICE

ABRAHAM SAVITZKY, OF NEW YORK, N. Y.

FINDING FOR CLASPS

Application filed October 28, 1931. Serial No. 571,492.

This invention relates to new and useful improvements in a finding for a clasp.

The invention relates particularly to a finding which is composed of a backing member pivotally connected with a jaw member, means for urging said members together, and a stop for limiting closing of the members about said pivot.

In the trade, it is the custom to solder finding members upon the backs of ornamental members and the provision of the stop for preventing closing of the members causes the condition in which the backing member may be rested flat against the back of the ornament and readily soldered on. In practice, it is found quite often the backing members do not rest flat against the back of the ornamental member. The cause of this may be a slightly bent ornamental member or jaw member on the finding. It is an object of this invention to construct a stop which is resilient so as to allow a certain amount of forced relative movements between the backing member and the jaw member to provide for the backing member assuming a flat position against the back of the ornament. This facilitates the soldering.

As another object of this invention it is proposed to locate the stop of the finding in a manner so that the finding may be manufactured at a minimum cost.

As a still further object of this invention it is proposed to construct the means for urging the members together in the form of a flat spring and to mount the stop upon the spring in a manner so that the jaw member is limited to close to a position substantially parallel with the flat spring, and in turn, the flat spring carries the backing member so that it is substantially parallel to the spring.

For further comprehension of the invention, and of the objects and advantages thereof, reference will be had to the following description and accompanying drawings, and to the appended claims in which the various

novel features of the invention are more particularly set forth.

In the accompanying drawings forming a material part of this disclosure:—

Fig. 1 is a perspective view of a finding 50 constructed according to this invention.

Fig. 2 is a perspective view of the finding shown in Fig. 1 viewed from the back.

Fig. 3 is a fragmentary sectional view taken on the line 3—3 of Fig. 1. 55

The finding consists of a backing member 10 pivotally connected with a jaw member 11. The backing member 10 is stamped from sheet material and is formed with side lugs 12 adapted to receive small projections 13 on 60 the sides of the jaw member 11. The jaw member is formed with several prongs 14 for engaging against the back of an ornament to clamp the ornament upon clothing. 65

A means is provided for urging the back 65 member and jaw member together. This means consists of a flat spring 15 located between the backing member and the jaw member.

The ends of the spring 15 are formed with 70 cutouts 16 producing prongs 17 engaging on opposite sides of a reduced neck 18 connecting the lugs 12 with the backing member. The prongs 17 thus hold the backing member 10 substantially parallel with the spring. 75 The spring 15 is of a slightly greater length than the distance between the reduced portions 18 of the backing member so as to be arched away from the backing member as clearly shown in Fig. 1. 80

The rear end of the jaw member 11 is formed with an upturned lip 19 engaging against the bottom rear edge of the spring 15. This lip is formed curved so as to allow opening of the jaw member 11 relative to the 85 backing member by reason of bowing the spring 15 upwards. In the closed position of the finding, the spring 15 presses downwards on the lip 19 so as to cause the main portion of the jaw member to tend to move 90

5 towards the backing member 15. A finger 20 projects from the edge of the spring 15 which is opposite the lip 19 and is directed down against the jaw member 11. Consequently, as the spring 15 tends to pivot the 10 jaw member 11 towards the backing member 10, the parts will be arrested and assume positions in which the backing member 10 is substantially parallel to the jaw member 11.

10 The arrangement of the stop member 20 upon the spring has several distinct advantages. One advantage is that the backing member 10 is resiliently held relative to the 15 jaw member 11. This allows rocking of the backing member relative to the jaw member within limits which does not cause the opening of the finding. Such rocking provides for the proper fitting of the backing member 20 on the rear of the ornament. A second advantage in the location of the stop finger 25 on the spring is that the finding may thus be manufactured at a cheaper price than if the stop finger were located on either the backing member or the jaw member. This is so in that the backing member and the jaw member is commercially formed of German silver of a gauge approximately .025 of an 30 inch and the spring is formed from high carbon steel approximately .012 of an inch. The cost of the German silver is materially 35 higher than the cost of the steel. Since the stop is located upon the spring and not the jaw or backing member, less material is needed on the jaw and backing members. More than this, since the stop is located on 40 the spring, it is of a smaller size than if located either on the backing member or jaw member and acting against the other.

45 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

50 Having thus described my invention, what I claim as new, and desire to secure by United States Letters Patent is:—

55 1. In a finding for clasps, a backing member, a jaw member pivotally connected with the backing member, a lip on one of said members near the pivot, a flat spring bowed between said lip and the other member and fixedly connected with the said member to close the front ends of said members and extending to the other side of said pivot, and 60 a finger projecting from the latter-mentioned side of said flat spring and engageable against the member formed with the lip to limit pivoting of the member to a position substantially parallel to the spring.

65 2. In a finding for clasps, a backing mem-

ber, a jaw member pivotally connected with said backing member, a lip on the rear end of the jaw member, a flat spring bowed between said lip and the backing member and having its ends relatively fixedly connected 70 with said backing member, and a finger projecting from said flat spring on the other side of the pivot between said members and said lip for acting against said jaw member.

75 In testimony whereof I affix my signature.

ABRAHAM SAVITZKY.
